(54) **PACKING SCREW, INVERTED**

(76) Inventor: **Stephen Terry**

Stephen Terry
Fellow's Patent

The Vochants referred to in their Fellow's Patent and marking part of the same containing a description, in the words of the said Stephen Terry himself, of his improvement in the inverted packing screw for packing cotton

To all to whom these presents shall come. Be it known that I, Stephen Terry of the County of De Kalb and State of Georgia have invented a new and useful improvement in compressing a large quantity of Cotton into a small compact for the convenience of transportation and which improvement is denominated. The new invention is inverted packing screw propelle by water power and the following is a full and exact description. This machine is placed in a frame of the following dimensions (viz.) The frame is 20 feet long 12 feet wide 15 feet high from the bottom of the sill to the top of the plate with three or more upright posts (as the waterman may determine) made of timber 12 inches square except the sills which should be 12 by 14 inches. The water wheel is 5 feet in diameter made in the ordinary way of undershot water wheels with 16 buckets 3 feet radius in length the wheel is attached to a shaft 7 feet in length and 12 inches in diameter, by 2 arms 12 inches wide and 2 inches thick and 5 feet long, let through the shaft by a mortice 18 inches from the end which is to be supported on a stone pillar, in the end of which there is to be a gudgeon of iron 6 inches in diameter, the other end also to run on a gudgeon 3 1/2 inches square let into the shaft 15 inches with a round of 5 inches which must be nicely turned, with a square on the outside of the round of 8 inches and rest on a cross beam similar to the bridge of a mill. On the square end of the gudgeon there is fixed a small cog wheel 12 inches in diameter in which there are geogs which work successively two other cog wheels of the following dimensions (to wit) The shaft 7 feet long and 15 inches in diameter with a gudgeon on each end which must be perpendicular to the

The lower end of which is fastened in a cross sill extending from the two bottom sides and the upper end is similarly fastened in a cross sill at the top to which shaft is attached by two arms 22 inches wide two cog wheels each 4 feet in diameter with 32 cogs in each with the cogs pointing towards. The wheels to be fastened on the aforesaid arms by bolts & screws going through each wheel and arm leaving a space between the points of cogs of eleven inches, which two cog wheels are to be counteracted by the successive operation of the aforesaid cog wheel placed on the water shaft which is effected by a lever morticed in one of the uprights of the frame by means of a hatch. The aforesaid cog wheel is thrown at pleasure into one of the two cog wheels before mentioned where in the cogs of either wheel it leaves a space of $\frac{1}{4}$ of an inch clear of opposite one and then by letting the water on the wheel raises the top and prepares the machine for the reception of the cotton. When raised to a sufficient height fast on the cotton over the bridge by the aforesaid lever and throw the small cog wheel into the lower cog wheel and continue the water on the water wheel and you reverse the course of the tap and screw & pack the bag in Cotton, and upon the shaft to aforesaid immediately below the lower cog wheel to which the two cog wheels is affixed by means of the arms. There is a rollhouse 15 inches in diameter containing 4 rounds in which is a spur cog wheel attached to the lower end of the screw pin which spur wheel is eight feet in diameter and contains 12 cogs. which wheel is fastened to the screw pin by 2 arms 5 feet long 14 inches wide and 3 inches thick. The arms passing through the screw pin by mortises through the lower end of the screw pin which is 20 inches in diameter and within eight inches of the lower end of the screw. The screw pin is 15 feet in length and arms perpendicular with point upwards. in the lower end of which there is a quideon wheel worked in an iron which is fastened into a sill which is 12 by 14 inches square. 12 feet of the pin is 17 inches in diameter on which there is cut a screw thread of 6 inches rise and runs through the top which is 4 feet 6 inches thick and 3 feet wide and the top end of the screw is let into the bed with a round iron.

7 inches in length 18 inches in diameter and on the tenon there is an iron plate 1 inch thick and of the same diameter as the tenon and which works against a similar iron plate which is fastened on the bottom of the mortise in the bed. The top is 7 feet 6 inches in length to each end of which there is fastened a piece of timber 18 feet long 2 inches wide 4 1/4 inches thick let into the top by a shoulder on three sides leaving a space between the two pieces of 4 feet 8 1/2 inches which determining the length of the bale. and the two pieces of timber are fastened at the top end by a piece of timber 18 inches wide and 1 inch as thick, which is tenoned into the two pieces with a double tenon passing through the side pieces and beaded at the outside which each piece forms the follower, and the two side pieces before mentioned form the end of the bale. On the inside corners of the upright is a rabbit 1 1/2 inch deep the lower end of the two pieces of side being fastened to the top. When the bale is put in motion the top remains stationary and the top, the follower and side pieces ascend and descend as the screw is turned backwards or forwards. There is a frame fixed on the top of first described frame which is fastened to the first described frame lying across from one of the top plates to the other, through which the side pieces are to pass and for the bed to rest on. in this frame there are four uprights raised 1 1/2 feet long 3 1/2 inches wide and 6 inches thick and placed at sufficient distance for the side pieces and follower to pass through and are connected together at the top by two small cap plates to these posts are attached the sides of the bale and down and all the other necessary apparatus for packing. What I claim as my own invention and not previously known in the foregoing described machine is the mode of applying the water and the arrangement of all the gearing.

Witnessed this first day of April 1835. *Stephen Lucy* *W. M. C.*
